UNITED STATES PATENT OFFICE.

CHARLES F. MILLER, OF PAYETTE, IDAHO.

RAIL-JOINT.

1,335,693.

Specification of Letters Patent. Patented Mar. 30, 1920.

Application filed December 6, 1918. Serial No. 265,552.

To all whom it may concern:

Be it known that I, CHARLES F. MILLER, a citizen of the United States, residing at Payette, in the county of Canyon and State 5 of Idaho, have invented new and useful Improvements in Rail-Joints, of which the following is a specification.

This invention relates to new and useful 10 improvements in railway joints and the principal object of the invention is to provide improved splicing bars for holding the ends of the rails together.

Another object of the invention is to provide a device of this character which is 15 simple and durable in construction, reliable and efficient in operation and one which can be manufactured and placed upon the market at a minimum cost.

The invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote like or corresponding parts throughout the several views, and in which:—

Figure 1 is a perspective view of my complete invention.

Fig. 2 show the ends of two rails with the splicing bars removed.

Fig. 3 is a bottom view of one of the rails.

Fig. 4 is a cross section through Fig. 1.

Fig. 5 is a horizontal section through said Fig. 1.

In these views 1 indicates one rail and 40 2 the abutting rail. As shown the base flanges 3 of these rails are cut away at their ends so as to produce a portion 4 at the extreme end of each rail which has its edges parallel with the web 5 of the rail. This portion 4 is connected with the uncut portion of the base by the part 6 which has its edge inclined. It will thus be seen that the base part of each rail is of substantially 45 wedge shape with the face of the wedge ending in a rectangular part which is of substantially the same width as the tread portion 7 of the rail.

The rails are held together by a pair of 50 splicing plates 8 which are each composed of the vertical flange 9 which is adapted to engage the webs of the rail. To this

flange is connected a substantially V shape portion 10 which engages the base flange 3 of the rail. It will be seen that this V 60 shape portion receives the base flange and its lower part extends to the center of the base so that when the bars are in position the entire base is inclosed by said V shape portions. The bars are secured in place by 65 bolts passing through the openings 11 in the flanges 9 and the openings 12 in the webs of the rails. Other bolts pass through openings 13 in the V shape portions of the bars to hold these portions of the two bars together. These bolts pass under the rails. Midway the ends of the bars the space 70 formed by the V shape portion of each bar is reduced to form a rectangular recess 14 to receive the portion 4 of the rails and the V 75 shape recesses 15 to receive the portions 6 of the rails. The bottom face of each bar is provided with a straight central part 16 and upwardly inclined end parts 17 so that the central parts of said bars are of great 80 thickness so that the meeting ends of the rails are inclosed by the thickest part of the bars. This central part is provided with a pair of ears 18 forming a recess to receive 85 a spike. The rail joint is adapted to rest upon a tie which is of less height than the other ties.

It is thought from the foregoing description that the advantages and novel features 90 of my invention will be readily apparent.

I desire it to be understood that I may make changes in the construction and in the combination and arrangement of the several parts, provided that such changes fall within the scope of the appended claim.

I claim as my invention:

A rail joint comprising a pair of rails each having its base flange reduced in width at the ends to produce an end portion with parallel edges and an adjacent portion with 100 flaring edges, a pair of splicing bars engaging said rails, each bar having an upper flange engaging the webs of the rail and a lower portion engaging the base flanges, said lower portion having a recess therein 105 formed with a straight center wall and outwardly flaring end walls to receive the parallel and flaring edges of the base flanges and bolts passing through the upper flanges and webs of the rails and bolts passing 110 through the lower portions and under the rails.

In testimony whereof I affix my signature.
CHARLES F. MILLER.
